(57) **CLAIM**

The ornamental design for ear and mouthpiece barriers for a phone, as shown and described.

DESCRIPTION

FIG. 1 is a front view of ear and mouthpiece barriers for a phone showing my new design.

FIG. 2 is a rear view of the ear and mouthpiece barriers for a phone.

FIG. 3 is a side view of the ear and mouthpiece barriers for a phone.

FIG. 4 is a top view of the ear and mouthpiece barriers for a phone; and,

FIG. 5 is a perspective view of the ear and mouthpiece barriers for a phone.

The broken lines of FIG. 5 illustrating a phone are for illustrative purposes and form no part of the claimed invention.
